[57] CLAIM

The ornamental design for a filing tray, substantially as shown and described.

DESCRIPTION

FIG. 1 is a perspective view of a filing tray, showing our new design.

FIG. 2 is a top plan view of the filing tray of FIG. 1.
FIG. 3 is a left side elevational view, the right side being a mirror image thereof.

FIG. 4 is a front elevational view.

FIG. 5 is a rear elevational view.

FIG. 6 is a bottom plan view.
